RESILIENT NO-BACK DEVICE FOR SMALL SYNCHRONOUS MOTORS

Nelson C. Spring, Jr., Terryville, and Christian M. J. Jauch, Torrington, Conn., assignors to General Time Corporation, New York, N.Y., a corporation of Delaware

Filed Feb. 10, 1964, Ser. No. 343,819
7 Claims. (Cl. 310—41)

This invention relates to an improved unidirectional drive for use with an inductor motor and particularly to a self-starting synchronous motor capable of starting in either direction. Devices of this type are commonly known as no-back mechanisms.

As is well known, motors of this type incorporate a multi-polar field wherein alternate poles possess opposite polarity at a particular instant and change polarity in accord with alternating current applied to an associated field coil. The poles of a magnetized rotor cooperate with the alternate poles for purposes of driving the rotor which in turn drives a shaft or spindle with a pinion fixed thereto. The pinion then drives a gear train that ultimately turns an output shaft which drives a load.

In known motors of this type, the rotor is invariably integral with the pinion drive spindle and a no-back mechanism is usually associated therewith. Such mechanism generally incorporates one or more stop members which collide when the rotor starts in the undesired direction and a ratcheting effect ensues when the rotor starts and continues rotation in the desired direction. In the event of collision, the resulting kick-back to the rotor results in reversal thereof and it maintains rotation in the desired direction.

Generally, such mechanisms incorporate an appreciable time lag prior to effectiveness, produce objectionable noise during operation, and are subject to wear which not only detracts from operational efficiency but frequently results in breakage of the parts. Motors of the collision no-back type are exemplified in patents issued to E. L. Schellens, 2,436,231; E. H. Gates, Jr., 2,722,297; P. H. Morganson, 2,722,615; R. G. Tetro, 2,789,673.

Another type of no-back mechanism may be found in Patent 2,788,455 issued to W. Kohlhgen. This patent discloses a spring-loaded cam that cooperates with a disc, both of undisclosed substance. The disc is fixed on the output shaft which is fast on the last gear in the output train. This arrangement is supplemented by an intricately formed spring that acts as a stored energy medium. The spring cooperates with a pair of slots formed in an intermediate gear of the drive train. The combination is interdependent for effecting the no-back function. The principle of a spring-loaded cam cooperating with a disc without a supplemental means such as above outlined has proved to be unsatisfactory for many reasons. The most serious reason being motor stall due to locking of the cam and disc when the rotor starts in the undesired direction. Another reason being due to flat spots that are developed either on the disc or cam after the motor has been repeatedly subject to no-back operations. The latter condition not only contributes to motor stall but in noisy operation of the motor during performance.

The present invention contemplates a no-back mechanism of extreme simplicity wherein a simple ring of resilient material, commonly known as an O ring, is mounted integral with the motor rotor assembly. A spring-loaded, toothed pawl cooperates with the periphery of the O ring for insuring unidirectional rotation of the rotor, as will be more fully explained hereinafter. This arrangement not only overcomes the deficiencies of previous no-back devices, some of which are mentioned

2

above, but can be adapted at a fraction of their expense.

Accordingly, it is the prime object of this invention to provide a self-starting synchronous motor with a directional drive control that is simple, reliable and efficient.

5 A further object is to provide a no-back mechanism that is "silent" during arresting action and during operation.

A still further object is to provide a self-starting synchronous motor wherein the rotor is arrested immediately 10 if it starts rotation in the undesired direction.

In keeping with the above object, a further object is in the provision of a toothed pawl and resilient ring whereby engagement of toothed pawl with ring is not restricted to a specific area of the ring.

15 It is a related object to provide a no-back mechanism that can be readily adapted to existing motors with a minimum of modification to such motors.

A still further object is to provide a motor that can be run in either direction with a minimum of modification.

20 Finally, it is an object of substantial importance to provide a no-back mechanism employing the absolute minimum of parts that are free of close tolerance necessity.

Other objects and advantages of the invention will be 25 come apparent upon reading the following detailed description and upon reference to the drawings in which:

FIG. 1 is an enlarged plan view of a motor embodying the present invention as taken along the lines 1—1 of FIG. 2 and illustrating the elements thereof in quiescent condition;

30 FIG. 2 is a sectional view thereof as taken substantially along the lines 2—2 of FIG. 1;

FIG. 3 is a plan view of an O ring used in carrying out the invention;

35 FIG. 4 is a detail front sectional elevation illustrating the O ring of FIG. 3 as assembled on the rotor assembly;

FIG. 5 illustrates the rotor assembly at the point of momentary arrest subsequent to its start of rotation in the undesired direction;

40 FIG. 6 illustrates the rotor assembly rotating in the desired direction immediately following the arresting action of FIG. 5;

FIG. 7 is a detail view showing the toothed pawl reversed from the FIG. 1 position so that the desired rotation of the rotor is opposite to that of FIG. 1.

Referring to the drawings, numeral 10 indicates a conventional shaded pole, self-starting synchronous motor which includes primary pole pieces 12 and shaded pole pieces 14. A shading ring 16 is provided between the base portions 13 and 15 of the primary and shaded pole pieces, respectively. Ring 16 serves to slightly delay the flux path to the shaded poles 14 via a housing cup member 17. The shaded poles 14 maintain a magnetizing influence on a permanent magnet rotor 18 of an assembly 20 for sustaining unidirectional rotation thereof once the rotor assembly gets underway, as is well known. A sizing ring 22 is fitted about pole pieces 12 and 14 for alignment and to insure the proper air gap between pole pieces and rotor.

50 A non-metallic bracing washer 24 seats between the base 13 of the primary pole pieces and bobbin 26 that houses an energizing coil 28. A core 30 is inserted through a central aperture of bobbin 26. Core 30 is staked at its upper end to the base portion 15 of the shaded pole pieces and at its lower end core 30 is staked to a gear train housing 32 which encloses the usual gear train, indicated at 34. Core 30, pole pieces 12, 14, ring 16 and the coil accommodating bobbin 26 are thus rigidly retained. A pair of bearings 36 are likewise fixed within the central bore in core 30 to accommodate a driving spindle 38.

65 At its upper end, spindle 38 supports permanent magnet 39 which is secured to the base portion 15 of the shaded pole pieces. A gear train 40 is secured to the lower end of spindle 38 and is in mesh with a pinion 42 which is secured to the output shaft 44. A pinion 46 is secured to the output shaft 44 and meshes with a gear 48 which is secured to the output shaft 50. A pinion 52 is secured to the output shaft 50 and meshes with a gear 54 which is secured to the output shaft 56. A pinion 58 is secured to the output shaft 56 and meshes with a gear 60 which is secured to the output shaft 62. A pinion 64 is secured to the output shaft 62 and meshes with a gear 66 which is secured to the output shaft 68. A pinion 70 is secured to the output shaft 68 and meshes with a gear 72 which is secured to the output shaft 74. A pinion 76 is secured to the output shaft 74 and meshes with a gear 78 which is secured to the output shaft 80. A pinion 82 is secured to the output shaft 80 and meshes with a gear 84 which is secured to the output shaft 86. A pinion 90 is secured to the output shaft 86 and meshes with a gear 92 which is secured to the output shaft 94. A pinion 96 is secured to the output shaft 94 and meshes with a gear 98 which is secured to the output shaft 100. A pinion 104 is secured to the output shaft 100 and meshes with a gear 106 which is secured to the output shaft 108. A pinion 110 is secured to the output shaft 108 and meshes with a gear 112 which is secured to the output shaft 114. A pinion 116 is secured to the output shaft 114 and meshes with a gear 118 which is secured to the output shaft 120. A pinion 124 is secured to the output shaft 120 and meshes with a gear 126 which is secured to the output shaft 128. A pinion 132 is secured to the output shaft 128 and meshes with a gear 134 which is secured to the output shaft 136. A pinion 140 is secured to the output shaft 136 and meshes with a gear 142 which is secured to the output shaft 144. A pinion 146 is secured to the output shaft 144 and meshes with a gear 148 which is secured to the output shaft 150. A pinion 154 is secured to the output shaft 150 and meshes with a gear 156 which is secured to the output shaft 158. A pinion 164 is secured to the output shaft 158 and meshes with a gear 166 which is secured to the output shaft 170. A pinion 174 is secured to the output shaft 170 and meshes with a gear 176 which is secured to the output shaft 180. A pinion 184 is secured to the output shaft 180 and meshes with a gear 186 which is secured to the output shaft 190. A pinion 196 is secured to the output shaft 190 and meshes with a gear 198 which is secured to the output shaft 200. A pinion 204 is secured to the output shaft 200 and meshes with a gear 206 which is secured to the output shaft 210. A pinion 214 is secured to the output shaft 210 and meshes with a gear 216 which is secured to the output shaft 220. A pinion 224 is secured to the output shaft 220 and meshes with a gear 226 which is secured to the output shaft 230. A pinion 234 is secured to the output shaft 230 and meshes with a gear 236 which is secured to the output shaft 240. A pinion 244 is secured to the output shaft 240 and meshes with a gear 246 which is secured to the output shaft 250. A pinion 254 is secured to the output shaft 250 and meshes with a gear 256 which is secured to the output shaft 260. A pinion 264 is secured to the output shaft 260 and meshes with a gear 266 which is secured to the output shaft 270. A pinion 274 is secured to the output shaft 270 and meshes with a gear 276 which is secured to the output shaft 280. A pinion 284 is secured to the output shaft 280 and meshes with a gear 286 which is secured to the output shaft 290. A pinion 294 is secured to the output shaft 290 and meshes with a gear 296 which is secured to the output shaft 300. A pinion 304 is secured to the output shaft 300 and meshes with a gear 306 which is secured to the output shaft 310. A pinion 314 is secured to the output shaft 310 and meshes with a gear 316 which is secured to the output shaft 320. A pinion 324 is secured to the output shaft 320 and meshes with a gear 326 which is secured to the output shaft 330. A pinion 334 is secured to the output shaft 330 and meshes with a gear 336 which is secured to the output shaft 340. A pinion 344 is secured to the output shaft 340 and meshes with a gear 346 which is secured to the output shaft 350. A pinion 354 is secured to the output shaft 350 and meshes with a gear 356 which is secured to the output shaft 360. A pinion 364 is secured to the output shaft 360 and meshes with a gear 366 which is secured to the output shaft 370. A pinion 374 is secured to the output shaft 370 and meshes with a gear 376 which is secured to the output shaft 380. A pinion 384 is secured to the output shaft 380 and meshes with a gear 386 which is secured to the output shaft 390. A pinion 394 is secured to the output shaft 390 and meshes with a gear 396 which is secured to the output shaft 400. A pinion 404 is secured to the output shaft 400 and meshes with a gear 406 which is secured to the output shaft 410. A pinion 414 is secured to the output shaft 410 and meshes with a gear 416 which is secured to the output shaft 420. A pinion 424 is secured to the output shaft 420 and meshes with a gear 426 which is secured to the output shaft 430. A pinion 434 is secured to the output shaft 430 and meshes with a gear 436 which is secured to the output shaft 440. A pinion 444 is secured to the output shaft 440 and meshes with a gear 446 which is secured to the output shaft 450. A pinion 454 is secured to the output shaft 450 and meshes with a gear 456 which is secured to the output shaft 460. A pinion 464 is secured to the output shaft 460 and meshes with a gear 466 which is secured to the output shaft 470. A pinion 474 is secured to the output shaft 470 and meshes with a gear 476 which is secured to the output shaft 480. A pinion 484 is secured to the output shaft 480 and meshes with a gear 486 which is secured to the output shaft 490. A pinion 494 is secured to the output shaft 490 and meshes with a gear 496 which is secured to the output shaft 500. A pinion 504 is secured to the output shaft 500 and meshes with a gear 506 which is secured to the output shaft 510. A pinion 514 is secured to the output shaft 510 and meshes with a gear 516 which is secured to the output shaft 520. A pinion 524 is secured to the output shaft 520 and meshes with a gear 526 which is secured to the output shaft 530. A pinion 534 is secured to the output shaft 530 and meshes with a gear 536 which is secured to the output shaft 540. A pinion 544 is secured to the output shaft 540 and meshes with a gear 546 which is secured to the output shaft 550. A pinion 554 is secured to the output shaft 550 and meshes with a gear 556 which is secured to the output shaft 560. A pinion 564 is secured to the output shaft 560 and meshes with a gear 566 which is secured to the output shaft 570. A pinion 574 is secured to the output shaft 570 and meshes with a gear 576 which is secured to the output shaft 580. A pinion 584 is secured to the output shaft 580 and meshes with a gear 586 which is secured to the output shaft 590. A pinion 594 is secured to the output shaft 590 and meshes with a gear 596 which is secured to the output shaft 600. A pinion 604 is secured to the output shaft 600 and meshes with a gear 606 which is secured to the output shaft 610. A pinion 614 is secured to the output shaft 610 and meshes with a gear 616 which is secured to the output shaft 620. A pinion 624 is secured to the output shaft 620 and meshes with a gear 626 which is secured to the output shaft 630. A pinion 634 is secured to the output shaft 630 and meshes with a gear 636 which is secured to the output shaft 640. A pinion 644 is secured to the output shaft 640 and meshes with a gear 646 which is secured to the output shaft 650. A pinion 654 is secured to the output shaft 650 and meshes with a gear 656 which is secured to the output shaft 660. A pinion 664 is secured to the output shaft 660 and meshes with a gear 666 which is secured to the output shaft 670. A pinion 674 is secured to the output shaft 670 and meshes with a gear 676 which is secured to the output shaft 680. A pinion 684 is secured to the output shaft 680 and meshes with a gear 686 which is secured to the output shaft 690. A pinion 694 is secured to the output shaft 690 and meshes with a gear 696 which is secured to the output shaft 700. A pinion 704 is secured to the output shaft 700 and meshes with a gear 706 which is secured to the output shaft 710. A pinion 714 is secured to the output shaft 710 and meshes with a gear 716 which is secured to the output shaft 720. A pinion 724 is secured to the output shaft 720 and meshes with a gear 726 which is secured to the output shaft 730. A pinion 734 is secured to the output shaft 730 and meshes with a gear 736 which is secured to the output shaft 740. A pinion 744 is secured to the output shaft 740 and meshes with a gear 746 which is secured to the output shaft 750. A pinion 754 is secured to the output shaft 750 and meshes with a gear 756 which is secured to the output shaft 760. A pinion 764 is secured to the output shaft 760 and meshes with a gear 766 which is secured to the output shaft 770. A pinion 774 is secured to the output shaft 770 and meshes with a gear 776 which is secured to the output shaft 780. A pinion 784 is secured to the output shaft 780 and meshes with a gear 786 which is secured to the output shaft 790. A pinion 794 is secured to the output shaft 790 and meshes with a gear 796 which is secured to the output shaft 800. A pinion 804 is secured to the output shaft 800 and meshes with a gear 806 which is secured to the output shaft 810. A pinion 814 is secured to the output shaft 810 and meshes with a gear 816 which is secured to the output shaft 820. A pinion 824 is secured to the output shaft 820 and meshes with a gear 826 which is secured to the output shaft 830. A pinion 834 is secured to the output shaft 830 and meshes with a gear 836 which is secured to the output shaft 840. A pinion 844 is secured to the output shaft 840 and meshes with a gear 846 which is secured to the output shaft 850. A pinion 854 is secured to the output shaft 850 and meshes with a gear 856 which is secured to the output shaft 860. A pinion 864 is secured to the output shaft 860 and meshes with a gear 866 which is secured to the output shaft 870. A pinion 874 is secured to the output shaft 870 and meshes with a gear 876 which is secured to the output shaft 880. A pinion 884 is secured to the output shaft 880 and meshes with a gear 886 which is secured to the output shaft 890. A pinion 894 is secured to the output shaft 890 and meshes with a gear 896 which is secured to the output shaft 900. A pinion 904 is secured to the output shaft 900 and meshes with a gear 906 which is secured to the output shaft 910. A pinion 914 is secured to the output shaft 910 and meshes with a gear 916 which is secured to the output shaft 920. A pinion 924 is secured to the output shaft 920 and meshes with a gear 926 which is secured to the output shaft 930. A pinion 934 is secured to the output shaft 930 and meshes with a gear 936 which is secured to the output shaft 940. A pinion 944 is secured to the output shaft 940 and meshes with a gear 946 which is secured to the output shaft 950. A pinion 954 is secured to the output shaft 950 and meshes with a gear 956 which is secured to the output shaft 960. A pinion 964 is secured to the output shaft 960 and meshes with a gear 966 which is secured to the output shaft 970. A pinion 974 is secured to the output shaft 970 and meshes with a gear 976 which is secured to the output shaft 980. A pinion 984 is secured to the output shaft 980 and meshes with a gear 986 which is secured to the output shaft 990. A pinion 994 is secured to the output shaft 990 and meshes with a gear 996 which is secured to the output shaft 1000.

At its upper end, spindle 38 supports permanent magnet 39 which is secured to the base portion 15 of the shaded pole pieces. A gear train 40 is secured to the lower end of spindle 38 and is in mesh with a pinion 42 which is secured to the output shaft 44. A pinion 46 is secured to the output shaft 44 and meshes with a gear 48 which is secured to the output shaft 50. A pinion 52 is secured to the output shaft 50 and meshes with a gear 54 which is secured to the output shaft 56. A pinion 58 is secured to the output shaft 56 and meshes with a gear 60 which is secured to the output shaft 62. A pinion 64 is secured to the output shaft 62 and meshes with a gear 66 which is secured to the output shaft 68. A pinion 70 is secured to the output shaft 68 and meshes with a gear 72 which is secured to the output shaft 74. A pinion 76 is secured to the output shaft 74 and meshes with a gear 78 which is secured to the output shaft 80. A pinion 82 is secured to the output shaft 80 and meshes with a gear 84 which is secured to the output shaft 86. A pinion 88 is secured to the output shaft 86 and meshes with a gear 90 which is secured to the output shaft 92. A pinion 96 is secured to the output shaft 92 and meshes with a gear 98 which is secured to the output shaft 100. A pinion 104 is secured to the output shaft 100 and meshes with a gear 106 which is secured to the output shaft 108. A pinion 110 is secured to the output shaft 108 and meshes with a gear 112 which is secured to the output shaft 114. A pinion 116 is secured to the output shaft 114 and meshes with a gear 118 which is secured to the output shaft 120. A pinion 124 is secured to the output shaft 120 and meshes with a gear 126 which is secured to the output shaft 128. A pinion 132 is secured to the output shaft 128 and meshes with a gear 134 which is secured to the output shaft 136. A pinion 140 is secured to the output shaft 136 and meshes with a gear 142 which is secured to the output shaft 144. A pinion 146 is secured to the output shaft 144 and meshes with a gear 148 which is secured to the output shaft 150. A pinion 154 is secured to the output shaft 150 and meshes with a gear 156 which is secured to the output shaft 158. A pinion 164 is secured to the output shaft 158 and meshes with a gear 166 which is secured to the output shaft 160. A pinion 174 is secured to the output shaft 160 and meshes with a gear 176 which is secured to the output shaft 170. A pinion 184 is secured to the output shaft 170 and meshes with a gear 186 which is secured to the output shaft 180. A pinion 194 is secured to the output shaft 180 and meshes with a gear 196 which is secured to the output shaft 190. A pinion 204 is secured to the output shaft 190 and meshes with a gear 206 which is secured to the output shaft 200. A pinion 214 is secured to the output shaft 200 and meshes with a gear 216 which is secured to the output shaft 210. A pinion 224 is secured to the output shaft 210 and meshes with a gear 226 which is secured to the output shaft 220. A pinion 234 is secured to the output shaft 220 and meshes with a gear 236 which is secured to the output shaft 230. A pinion 244 is secured to the output shaft 230 and meshes with a gear 246 which is secured to the output shaft 240. A pinion 254 is secured to the output shaft 240 and meshes with a gear 256 which is secured to the output shaft 250. A pinion 264 is secured to the output shaft 250 and meshes with a gear 266 which is secured to the output shaft 260. A pinion 274 is secured to the output shaft 260 and meshes with a gear 276 which is secured to the output shaft 270. A pinion 284 is secured to the output shaft 270 and meshes with a gear 286 which is secured to the output shaft 280. A pinion 294 is secured to the output shaft 280 and meshes with a gear 296 which is secured to the output shaft 290. A pinion 304 is secured to the output shaft 290 and meshes with a gear 306 which is secured to the output shaft 310. A pinion 314 is secured to the output shaft 310 and meshes with a gear 316 which is secured to the output shaft 320. A pinion 324 is secured to the output shaft 320 and meshes with a gear 326 which is secured to the output shaft 330. A pinion 334 is secured to the output shaft 330 and meshes with a gear 336 which is secured to the output shaft 340. A pinion 344 is secured to the output shaft 340 and meshes with a gear 346 which is secured to the output shaft 350. A pinion 354 is secured to the output shaft 350 and meshes with a gear 356 which is secured to the output shaft 360. A pinion 364 is secured to the output shaft 360 and meshes with a gear 366 which is secured to the output shaft 370. A pinion 374 is secured to the output shaft 370 and meshes with a gear 376 which is secured to the output shaft 380. A pinion 384 is secured to the output shaft 380 and meshes with a gear 386 which is secured to the output shaft 390. A pinion 394 is secured to the output shaft 390 and meshes with a gear 396 which is secured to the output shaft 400. A pinion 404 is secured to the output shaft 400 and meshes with a gear 406 which is secured to the output shaft 410. A pinion 414 is secured to the output shaft 410 and meshes with a gear 416 which is secured to the output shaft 420. A pinion 424 is secured to the output shaft 420 and meshes with a gear 426 which is secured to the output shaft 430. A pinion 434 is secured to the output shaft 430 and meshes with a gear 436 which is secured to the output shaft 440. A pinion 444 is secured to the output shaft 440 and meshes with a gear 446 which is secured to the output shaft 450. A pinion 454 is secured to the output shaft 450 and meshes with a gear 456 which is secured to the output shaft 460. A pinion 464 is secured to the output shaft 460 and meshes with a gear 466 which is secured to the output shaft 470. A pinion 474 is secured to the output shaft 470 and meshes with a gear 476 which is secured to the output shaft 480. A pinion 484 is secured to the output shaft 480 and meshes with a gear 486 which is secured to the output shaft 490. A pinion 494 is secured to the output shaft 490 and meshes with a gear 496 which is secured to the output shaft 500. A pinion 504 is secured to the output shaft 500 and meshes with a gear 506 which is secured to the output shaft 510. A pinion 514 is secured to the output shaft 510 and meshes with a gear 516 which is secured to the output shaft 520. A pinion 524 is secured to the output shaft 520 and meshes with a gear 526 which is secured to the output shaft 530. A pinion 534 is secured to the output shaft 530 and meshes with a gear 536 which is secured to the output shaft 540. A pinion 544 is secured to the output shaft 540 and meshes with a gear 546 which is secured to the output shaft 550. A pinion 554 is secured to the output shaft 550 and meshes with a gear 556 which is secured to the output shaft 560. A pinion 564 is secured to the output shaft 560 and meshes with a gear 566 which is secured to the output shaft 570. A pinion 574 is secured to the output shaft 570 and meshes with a gear 576 which is secured to the output shaft 580. A pinion 584 is secured to the output shaft 580 and meshes with a gear 586 which is secured to the output shaft 590. A pinion 594 is secured to the output shaft 590 and meshes with a gear 596 which is secured to the output shaft 600. A pinion 604 is secured to the output shaft 600 and meshes with a gear 606 which is secured to the output shaft 610. A pinion 614 is secured to the output shaft 610 and meshes with a gear 616 which is secured to the output shaft 620. A pinion 624 is secured to the output shaft 620 and meshes with a gear 626 which is secured to the output shaft 630. A pinion 634 is secured to the output shaft 630 and meshes with a gear 636 which is secured to the output shaft 640. A pinion 644 is secured to the output shaft 640 and meshes with a gear 646 which is secured to the output shaft 650. A pinion 654 is secured to the output shaft 650 and meshes with a gear 656 which is secured to the output shaft 660. A pinion 664 is secured to the output shaft 660 and meshes with a gear 666 which is secured to the output shaft 670. A pinion 674 is secured to the output shaft 670 and meshes with a gear 676 which is secured to the output shaft 680. A pinion 684 is secured to the output shaft 680 and meshes with a gear 686 which is secured to the output shaft 690. A pinion 694 is secured to the output shaft 690 and meshes with a gear 696 which is secured to the output shaft 700. A pinion 704 is secured to the output shaft 700 and meshes with a gear 706 which is secured to the output shaft 710. A pinion 714 is secured to the output shaft 710 and meshes with a gear 716 which is secured to the output shaft 720. A pinion 724 is secured to the output shaft 720 and meshes with a gear 726 which is secured to the output shaft 730. A pinion 734 is secured to the output shaft 730 and meshes with a gear 736 which is secured to the output shaft 740. A pinion 744 is secured to the output shaft 740 and meshes with a gear 746 which is secured to the output shaft 750. A pinion 754 is secured to the output shaft 750 and meshes with a gear 756 which is secured to the output shaft 760. A pinion 764 is secured to the output shaft 760 and meshes with a gear 766 which is secured to the output shaft 770. A pinion 774 is secured to the output shaft 770 and meshes with a gear 776 which is secured to the output shaft 780. A pinion 784 is secured to the output shaft 780 and meshes with a gear 786 which is secured to the output shaft 790. A pinion 794 is secured to the output shaft 790 and meshes with a gear 796 which is secured to the output shaft 800. A pinion 804 is secured to the output shaft 800 and meshes with a gear 806 which is secured to the output shaft 810. A pinion 814 is secured to the output shaft 810 and meshes with a gear 816 which is secured to the output shaft 820. A pinion 824 is secured to the output shaft 820 and meshes with a gear 826 which is secured to the output shaft 830. A pinion 834 is secured to the output shaft 830 and meshes with a gear 836 which is secured to the output shaft 840. A pinion 844 is secured to the output shaft 840 and meshes with a gear 846 which is secured to the output shaft 850. A pinion 854 is secured to the output shaft 850 and meshes with a gear 856 which is secured to the output shaft 860. A pinion 864 is secured to the output shaft 860 and meshes with a gear 866 which is secured to the output shaft 870. A pinion 874 is secured to the output shaft 870 and meshes with a gear 876 which is secured to the output shaft 880. A pinion 884 is secured to the output shaft 880 and meshes with a gear 886 which is secured to the output shaft 890. A pinion 894 is secured to the output shaft 890 and meshes with a gear 896 which is secured to the output shaft 900. A pinion 904 is secured to the output shaft 900 and meshes with a gear 906 which is secured to the output shaft 910. A pinion 914 is secured to the output shaft 910 and meshes with a gear 916 which is secured to the output shaft 920. A pinion 924 is secured to the output shaft 920 and meshes with a gear 926 which is secured to the output shaft 930. A pinion 934 is secured to the output shaft 930 and meshes with a gear 936 which is secured to the output shaft 940. A pinion 944 is secured to the output shaft 940 and meshes with a gear 946 which is secured to the output shaft 950. A pinion 954 is secured to the output shaft 950 and meshes with a gear 956 which is secured to the output shaft 960. A pinion 964 is secured to the output shaft 960 and meshes with a gear 966 which is secured to the output shaft 970. A pinion 974 is secured to the output shaft 970 and meshes with a gear 976 which is secured to the output shaft 980. A pinion 984 is secured to the output shaft 980 and meshes with a gear 986 which is secured to the output shaft 990. A pinion 994 is secured to the output shaft 990 and meshes with a gear 996 which is secured to the output shaft 1000.

At its upper end, spindle 38 supports permanent magnet 39 which is secured to the base portion 15 of the shaded pole pieces. A gear train 40 is secured to the lower end of spindle 38 and is in mesh with a pinion 42 which is secured to the output shaft 44. A pinion 46 is secured to the output shaft 44 and meshes with a gear 48 which is secured to the output shaft 50. A pinion 52 is secured to the output shaft 50 and meshes with a gear 54 which is secured to the output shaft 56. A pinion 58 is secured to the output shaft 56 and meshes with a gear 60 which is secured to the output shaft 62. A pinion 64 is secured to the output shaft 62 and meshes with a gear 66 which is secured to the output shaft 68. A pinion 70 is secured to the output shaft 68 and meshes with a gear 72 which is secured to the output shaft 74. A pinion 76 is secured to the output shaft 74 and meshes with a gear 78 which is secured to the output shaft 80. A pinion 82 is secured to the output shaft 80 and meshes with a gear 84 which is secured to the output shaft 86. A pinion 88 is secured to the output shaft 86 and meshes with a gear 90 which is secured to the output shaft 92. A pinion 96 is secured to the output shaft 92 and meshes with a gear 98 which is secured to the output shaft 100. A pinion 104 is secured to the output shaft 100 and meshes with a gear 106 which is secured to the output shaft 108. A pinion 110 is secured to the output shaft 108 and meshes with a gear 112 which is secured to the output shaft 114. A pinion 116 is secured to the output shaft 114 and meshes with a gear 118 which is secured to the output shaft 120. A pinion 124 is secured to the output shaft 120 and meshes with a gear 126 which is secured to the output shaft 128. A pinion 132 is secured to the output shaft 128 and meshes with a gear 134 which is secured to the output shaft 136. A pinion 140 is secured to the output shaft 136 and meshes with a gear 142 which is secured to the output shaft 144. A pinion 146 is secured to the output shaft 144 and meshes with a gear 148 which is secured to the output shaft 150. A pinion 154 is secured to the output shaft 150 and meshes with a gear 156 which is secured to the output shaft 158. A pinion 164 is secured to the output shaft 158 and meshes with a gear 166 which is secured to the output shaft 160. A pinion 174 is secured to the output shaft 160 and meshes with a gear 176 which is secured to the output shaft 170. A pinion 184 is secured to the output shaft 170 and meshes with a gear 186 which is secured to the output shaft 180. A pinion 194 is secured to the output shaft 180 and meshes with a gear 196 which is secured to the output shaft 190.

rotor 18, a formed disc 42 and a binding member 44. Disc 42 and rotor 18 are formed to accommodate and retain a resilient ring 46 which is mounted therebetween by stretching. Spindle 38, rotor 40, disc 42, member 44 and resilient ring 46 make up the rotor assembly 20. Resilient ring 46, commonly known as an O ring, may be of Buna N 70 rubber, a substance commercially known as neoprene, or any like material.

A pawl, preferably of molded Delrin, is pivotally mounted as at 50 on cup member 17 and is provided with teeth 52. Pawl 48 is gently urged counterclockwise (FIG. 1) by a torsion spring 54 so that teeth 52 lightly contact the periphery of resilient ring 46 for purpose of insuring predetermined directional rotation of the rotor assembly, as will be more fully explained below.

A pinion 54 is pressed on the lower end of spindle 38 and serves as the initial drive for gear train 34. Gear 56 serves to drive an output shaft 58 which may be coupled to a load. A motor cover 60 is frictionally pressed on member 17 to encase the upper region of the motor.

When coil 28 is energized from a power source via wires 62, the rotor assembly 20 immediately commences to rotate. With this type of motor, the rotor assembly is inclined to start and continue rotation in a predetermined or desired direction. However, such action cannot be guaranteed and the rotor frequently starts in the undesired direction, particularly if the torque requirement of the motor is high. Therefore, the novel rotation direction controlling means of resilient ring 46 and toothed pawl are provided so that the rotor assembly is restricted to rotation in one direction only, referred to herein as the desired direction. When restricted from rotation in the undesired direction, the rotor assembly will immediately reverse and continue to run in the opposite or desired direction.

Referring particularly to FIGS. 3 and 4, the angled portion 64 of rotor 18 is of slightly greater diameter than the inner diameter 66 of resilient ring 46 when said ring is in the relaxed condition. Accordingly, ring 46 is stretched and mounted between disc 42 and rotor 18, as best shown in FIG. 4, and thus frictionally retained against slippage or dislodgement.

In FIGS. 1, 2, 5 and 6, pawl 48 is mounted to insure counterclockwise rotation of rotor assembly 20. FIG. 5 illustrates the co-action of pawl 48 and resilient ring 46 as the rotor assembly 20 starts in the undesired direction from the FIG. 1 position. Immediately pawl 48 pivots from the position shown in FIG. 1 to the position shown in FIG. 5 and slightly compresses the contact area of ring 46 through the action of teeth 52. Such action prohibits rotation in the clockwise direction, and through the compressing action of resilient ring 46 at said contact area, impels or bounces the rotor assembly in the counterclockwise or desired direction, as indicated by the arrow in FIG. 6. It is important to note that the above action is "noiseless" and instantaneous; there is no appreciable time lag or lost motion effect in performing the no-back action. Furthermore, there is no restrictive area on the periphery of the resilient ring 46 that need be engaged by teeth 52 of pawl 48 and as the motor operates teeth 52 gently engage the periphery of ring 46 and also act to remove objectionable foreign matter such as lubricant deposits that tend to hinder performance. It can thus be appreciated that teeth 52 of pawl 48 not only serve to continually cleanse the periphery of ring 46 but are maintained in poised position to immediately interrupt rotor assembly 20 should it start in the undesired direction.

FIG. 7 illustrates the mounting of pawl 48 as adapted to a motor wherein the desired rotation of rotor assembly 20 is clockwise. Pawl 48 is merely mounted opposite to the position shown in FIG. 1 and a new spring 54a is added to provide the opposite torsional effect. The primary poles 12 and shaded poles 14 are alternately disposed in contrast to the FIG. 1 showing.

Thus with the novel arrangement of a simple O ring and a spring-urged toothed pawl, an efficient, quiet and extremely inexpensive no-back mechanism has been provided. Moreover, the random engagement feature insures long operational efficiency of the O ring and, should service need be administered to the no-back mechanism, all elements thereof are readily accessible and easily replaced at a bare minimum of cost and effort.

It should also be pointed out that pawl 48 may conceivably be of resilient material and mount pivotally as by a metal insert. Alternatively, the ring would be of a non-resilient material. With such arrangement operation is satisfactory but wear is concentrated at one area of the pawl and a shorter effective life of the arresting member of the no-back unit can be expected as contrasted by long operational efficiency afforded by random engagement of teeth 52 at the periphery of resilient ring 46.

Having described the invention by making detailed reference to preferred forms of the elements thereof it is obvious that various modifications may be made without departing from the spirit of the invention. It is therefore understood that this invention is not limited to the exact arrangement disclosed except as limited by the state of the art to which this invention pertains.

What is claimed is:

1. In a synchronous motor the combination of:

alternate field poles,
a rotatable permanent magnet rotor capable of starting and running in a first or a second direction on effecting alternating opposite polarities in said alternate field poles,

a resilient member rotatable with said rotor,
an element pivotally arranged adjacent said resilient member, and means on said pivotal element for arrestingly engaging and compressing said resilient member when said rotor rotates in said first direction whereupon said rotor is impelled in said second direction.

2. The combination defined in claim 1 including a spring biasingly engaged with said pivotal element and said means includes teeth which are biased by said spring toward said resilient member.

3. In a synchronous motor the combination of:

alternate field poles,
a rotor assembly including a permanent magnet rotor, said rotor assembly capable of starting and running in a first or a second direction when said permanent magnet rotor is affected by alternating opposite polarities in said alternate field poles,

a resilient ring frictionally mounted on said rotor assembly,
a pawl pivotally biased in abutment with said ring, and means on said pawl for arrestingly engaging and compressing a portion of said ring when said rotor assembly starts in said first direction whereupon said rotor assembly is impelled and continues to run in said second direction.

4. The combination defined in claim 3 wherein said means includes projections at least one of which brushes said ring while said rotor assembly runs in said second direction.

5. The combination defined in claim 3 wherein said rotor assembly includes a permanent magnet rotor portion and a formed disc portion integral with said rotor portion, and said frictionally mounted resilient ring is located between said permanent magnet rotor portion and said formed disc portion and retained against dislodgement on said rotor assembly by said formed disc portion.

6. In a synchronous motor the combination of:

alternate field poles,
a rotor assembly including a permanent magnet rotor, said rotor assembly capable of starting and running in a first or a second rotary direction when said permanent

5
ent magnet rotor is affected by alternating opposite polarities in said alternate field poles,
a rotor element unified with said rotor assembly,
a pawl arranged adjacent to and for engaging said rotor element,
and means on said pawl to effect a compressing engagement between said rotor element and said pawl means when said assembly starts in said first direction whereupon said rotor assembly is impelled toward and continues to run in said second direction. 10
7. In a synchronous motor the combination of:
alternate field poles,
a unitary rotor assembly including a permanent magnet rotor portion, a formed disc portion and a spindle portion,
said rotor assembly capable of starting and running in a desired or an undesired direction when said permanent magnet rotor is affected by alternating opposite polarities in said alternate field poles, 15

a resilient ring mounted on at least one portion of said rotor assembly,
a cup member partially enclosing said rotor assembly,
a pawl pivotally mounted on said cup member adjacent said ring,
a spring arranged between said cup member and said pawl to bias said pawl toward said ring,
and means on said pawl for arrestingly engaging and compressing said ring at one portion thereof when said rotor assembly starts in said undesired direction whereupon said rotor assembly is impelled toward and continues to run in said desired direction.
